HANGER

John E. Trottier, New York, N. Y., assignor of
one-half to Jeremiah Healy, Riverdale, N. Y.

Application January 22, 1935, Serial No. 2,865

4 Claims. (Cl. 211—107)

This invention relates to supports and more especially to a hanger for use in a military tent. In such tents, there is usually provided a central supporting pole or a horizontal bar and the hanger 5 of the present invention is particularly adapted for use in connection either with such pole or bar.

An object of this invention is an inexpensive light-weight and strong hanger which may easily 10 and quickly be attached to the tent pole or horizontal bar and has provision for supporting the standard broadbrim military hat in such position as to avoid any possibility of injury to the brim as well as provision for supporting clothes-hang- 15 ers.

A hanger embodying the invention consists essentially of a clamp rigidly attached to and 20 detachable from a support and having a plurality of radially extending arms, the ends of which are connected by rods to form a plurality of triangular frames, each of which is adapted to receive the crown of a hat with the brim resting on two arms and the rod associated therewith, the rod also being usable to support clothes-hang- 25 ers. Contact of the crown of the hat with the sides of the frame prevents lateral displacement thereof and the brim is arranged in flat position and protected against disfigurement.

Other objects, novel features and advantages 30 of this invention will become apparent from the following specification and accompanying drawing, wherein:

Fig. 1 is a plan of my hanger applied to a tent pole;

Fig. 2 is a partial elevation on line 2—2 of Fig. 1;

Fig. 3 is a section on the line 3—3 of Fig. 1;

Fig. 4 is a perspective view;

Fig. 5 is a fragmentary plan view of a modified 40 form, and

Fig. 6 is a section on the line 6—6 of Fig. 5.

In Figs. 1 to 4, a hanger embodying the invention is shown as attached to a tent pole 10. A two-part collar 11 is clamped to the pole 10 by means 45 of bolts 12 extending between corresponding ends of the two parts of the collar. Each collar part supports two arms 13, each arm comprising a short vertical portion which rests against the pole 10 and a longer portion extending horizontally from 50 the pole, the arms being equally spaced angularly.

Rods 14 extend between the outer ends of the arms 13 to form triangular supporting frames, the 5 ends of each rod 14 being detachably connected to the ends of the arms between which the rod 5 extends. The triangular supports formed by the

arms 13 and rods 14 are of proper size to receive the crown of a broad-brim military hat with the brim lying flat on the arms and rods in which position it is protected against disfigurement. Clothes hangers of the ordinary type may be 5 hooked on the rods 14 and also on the arms 13, if desired. The hanger thus provides for the support of the hats of soldiers occupying the tent and also their wearing apparel in a compact space.

In a typical example of the hanger, the rods 14 are each two feet long so that the entire device takes up but four square feet. The hanger is of knock-down construction so that when it is removed from the tent pole it may be stored in a 10 small space. The rods 14 may be disconnected from the arms 13 and if desired the arms 13 may be pivotally connected to the collar so that they may be swung together. Furthermore, the device is composed entirely of metal rods and bands 20 which can be inexpensively fabricated and the device can be therefore produced at a relatively low cost. Also, because of the fact that the device is made from metal rods, it has the requisite strength to support considerable weight.

The shape of the arms 13 tends to prevent any 25 possibility of the hanger sliding down the pole when weight is applied thereto. The elbows of the rods 13 will be forced tightly against the pole through the leverage of the horizontal part of the 30 arm when weight is applied to the outer ends of such arms by hanging of clothes on the rods 14. The binding action thus effected will supplement the clamping effect of the collar 11 and hold the hanger rigidly in position.

In the modification shown in Figs. 5 and 6, the hanger is supported from a horizontal beam 10a by collars 16 which surround the bar and support a flat rod 15. The collar 11 of the hanger is clamped to the rod 15 by bolts 12 and carries the 40 rods 13 as described previously, the ends of the rods 13 being connected by the rods 14. This modification is similar in structure to the first modification except that it has a different means of support.

It is to be understood that thumb screws may be used instead of the bolts 12 and likewise that a thumb screw may be used to connect one end of a rod 14 to the end of an arm 13, thus facilitating assembling and disassembling by obviating 50 the need of tools to connect or disconnect the parts.

It is of course further understood that various modifications may be made in the structure herein described, without in any way departing from 55

the spirit of the invention as defined in the appended claims.

The ends of two of the rods 14 are shown as being detachably connected to the end of an arm 13 by a standard bolt 17 provided with the usual nut, while the remaining ends of the various rods 14 are shown as being connected to the arms 13 10 that if desired, the rivets may be replaced either with standard bolts and nuts or thumb bolts and nuts and also that the bolt 17 may likewise be replaced by a thumb bolt.

I claim:

15 1. A hanger comprising a collar adapted to enclose and grip a vertical support, arms connected to said collar and having short vertical portions adapted to engage the support and long horizontal portions extending radially, and rods 20 connecting the free ends of said arms to define triangular frames.

2. A hanger comprising a collar adapted to enclose and grip a vertical support, arms con-

nected to said collar and having short vertical portions adapted to engage the support and long horizontal portions extending radially, and rods detachably connected at their ends to the free ends of said arms to define triangular frames. 5

3. A hanger comprising a split collar adapted to enclose a support, means for drawing the collar into clamping relation to the support, arms connected to said collar, said arms having short vertical portions adapted to engage the support and long horizontal portions extending radially, and rods connecting the free ends of said arms to define triangular frames.

4. A hanger comprising a split collar adapted to enclose a support, means for drawing the collar into clamping relation to the support, arms connected to said collar, said arms having short vertical portions adapted to engage the support and long horizontal portions extending radially, and rods detachably connected at their ends to the 15 20 free ends of said arms to define triangular frames.

JOHN E. TROTTIER.
